(57) **CLAIM**

The ornamental design for a floating support structure for a wind turbine, as shown and described.

DESCRIPTION

1. Floating support structure for a wind turbine
FIG. 1.1 is a left side elevation view of a floating support structure for a wind turbine;
FIG. 1.2 is a rear side elevation view thereof;
FIG. 1.3 is a right side elevation view thereof;
FIG. 1.4 is a front side elevation view thereof;
FIG. 1.5 is a bottom plan view thereof;
FIG. 1.6 is a top plan view thereof; and
FIG. 1.7 is a perspective view thereof.
The broken lines shown depict environmental subject matter and form no part of the claimed design.
